DRILL TOOL RETAINER

Filed Oct. 4, 1929

INVENTOR
GEORGE RAUBERSTRAUCH
BY *Rickey & Watts.*
ATTORNEY

UNITED STATES PATENT OFFICE

GEORGE RAUBERSTRAUCH, OF CLEVELAND, OHIO, ASSIGNOR TO THE CLEVELAND ROCK DRILL COMPANY, OF CLEVELAND, OHIO, A CORPORATION OF OHIO

DRILL TOOL RETAINER

Application filed October 4, 1929. Serial No. 397,181.

The present invention relates broadly to rock drills of the percussion type and more specifically to improvements in tool retainers.

One of the objects of this invention is to provide a releasable tool retainer which is simple in design, economic of manufacture, and susceptible of ready manipulation.

Another object is to provide a tool retainer which is organized to prevent the accidental disengagement of the tool from the drill.

Another object of the invention is to provide a tool retainer which can be readily affixed to or removed from the drill.

Other objects and advantages more or less ancillary to the foregoing and the manner in which the various objects are attained reside in the specific construction and aggroupment of the elements peculiar to the structure, as will become apparent from a more complete examination of this specification, in the claims of which there are assembled certain specific combinations of parts and specific constructions indicative of the scope and spirit of the invention.

In the drawing which illustrates a preferred embodiment of the invention

Fig. 1 is an elevational view of the lower portion of a percussion rock drill, provided with the improved tool retainer;

Fig. 2 is an elevational view taken at right angles to Figure 1;

Fig. 3 is an end elevation of the structure shown in Figure 2;

Fig. 4 is a sectional view taken on a plane indicated by the line 4-4 in Figure 2.

Referring to the drawing, in which like symbols designate corresponding parts throughout the several views, there is shown a head 10, constituting the lower portion of the casing of a percussive rock drill, and provided with oppositely disposed apertured ears 11 receiving bolts 12 for securing the head to the upper portions of the casing. A pair of diametrically opposed open ears 13 are formed on the head at right angles to

the ears 11, each of the ears 13 being provided with a pair of spaced notches 14 and 15.

A pair of inclined slots 16, having substantially parallel floor portions, are formed on opposite sides of the head beneath the ears 13. The inner termini of the slots 16 consist of a pair of diametrically opposed circular recesses 17, depressed slightly below the levels of the floor portions of the respective slots 16.

The tool retainer comprises a yoke 18 having a substantially semi-annular loop 19 and integral parallel arms 20 extending from the ends of the loop at substantially right angles to the plane thereof. The arms 20 are formed with inwardly extending trunnions 21 adapted to be journaled in the recesses 17. The free ends of the arms 20 beyond the trunnions 21 are arranged to fit within the ears 13 and to resiliently engage in the notches 14 or 15.

As is customary in machines of this type, the head 10 is provided with an axial opening to slidably receive the tool 22. The tool is formed with an integral collar 23 which engages the lower end of the head 10 to limit its sliding motion inwardly. When the machine is being operated, the tool rests upon the work and the body of the machine is supported by the tool. However, when operation ceases and it is desired to lift the drill from the work, some means must be provided to restrain the tool from sliding from the head and remaining in the hole which has been formed. Accordingly, the loop 19 is formed of such a diameter as to engage the collar 23 and restrain the tool from sliding outwardly from the head when the free ends of the arms 20 are retained in the notches 14, and is spaced from the lower edge of the head a sufficient distance to permit reciprocation of the tool during normal operation thereof.

When it is desired to remove the tool from the drill the parts being in the position shown

in full lines in Figure 1, the loop 19 is forced away from the tool to the dotted line position in Figure 1, the ends of the arms 20 snapping out of the notches 14 and into the spaced notches 15. To again lock the tool in position, the yoke is forced inwardly to its vertical position. When it is desired to remove the retainer from the drill, the yoke is forced outwardly until the arms 20 pass both sets of notches and clear the ears 13. The ends of the arms 20 are then spread until the trunnions 21 clear the recesses 17 and rest upon the floors of the slots 16. The trunnions are then slid outwardly through the slots 16. To replace the retainer, the trunnions are placed in the slots 16 by spreading the arms, and pushed inwardly through the slots until they snap into the recesses 17.

When the retainer is in either of its normal positions, with the arms 20 engaged in either pair of notches 14 or 15, it cannot be removed or accidentally disengaged from the drill, since the ears 13 prevent spreading of the arms sufficiently to release the trunnions from the recesses 17.

Although the foregoing description is necessarily of a detailed character in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

1. In a drill of the class described, a head, a yoke having arms embracing said head and pivoted thereto intermediate their length, means on the outer ends of said arms for retaining a tool, and means for engaging the outer side of the opposite end of one of said arms to releasably secure said yoke in a plurality of positions.

2. In a drill of the class described, a head slidably receiving a tool, a yoke including resilient arms pivoted to said head and rigid means on said head for engaging the outer side of said arms to releasably secure said yoke in any one of a plurality of positions.

3. In a drill, a head having a tool associated therewith, a yoke having resilient arms pivoted to said head, said yoke including means adapted to retain said tool in said head when said yoke is in one position and to release said tool when said yoke is in another position, and ears on said head adapted to engage the outer sides of said arms to releasably secure said yoke in either of said positions.

4. In a drill, a head having a tool associated therewith, recesses disposed in said head, a tool retaining yoke including a pair of resilient arms having inwardly extending trunnions thereon adapted to engage said recesses in said head, and means on said

head for engaging the outer sides of said arms for restraining the same against expansion to thereby lock said trunnions in said recesses.

5. In a drill, a head having a tool associated therewith, recesses disposed in said head, a yoke including a pair of resilient arms carrying tool retaining means at one end thereof and having inwardly extending trunnions intermediate their length adapted to engage said recesses in said head, and means on said head for engaging the outer sides of the free ends of said arms for restraining the same against expansion to thereby lock said trunnions in said recesses.

6. In a drill, a head having a tool associated therewith, recesses disposed in said head, a tool retaining yoke including a pair of resilient arms having inwardly extending trunnions adapted to engage said recesses in said head, and means on said head for engaging the outer sides of said arms for restraining the same against expansion, said means including notches for receiving said arms to releasably secure said yoke in any one of a plurality of positions.

7. In a drill, a head having a tool associated therewith, recesses disposed in said head, a yoke including a pair of resilient arms carrying tool retaining means at one end thereof and having inwardly extending trunnions intermediate their length adapted to engage said recesses in said head, and means on said head for engaging the outer sides of the free ends of said arms for restraining the same against expansion, said means including notches for receiving said arms to releasably secure said yoke in any one of a plurality of positions.

8. In a drill, a head having a tool associated therewith, a tool retainer including a pair of resilient arms adapted to embrace said head and having inwardly extending trunnions thereon, slots in said head adapted to receive said trunnions, and recesses depressed from said slots and adapted to retain said trunnions to pivotally mount said retainer on said head.

9. In a drill, a head having a tool associated therewith, a tool retaining yoke including a pair of resilient arms adapted to embrace said head and having inwardly extending trunnions thereon, slots in said head adapted to receive said trunnions and terminating in diametrically opposed recesses adapted to receive said trunnions and pivotally mount said yoke on said head, and means on said head for engaging the outer sides of said arms to restrain the same against expansion.

10. In a drill, a head having a tool associated therewith, a tool retaining yoke including a pair of resilient arms arranged to embrace said head and having inwardly extending trunnions intermediate the length

thereof, slots in said head to slidably receive said trunnions and terminating in diametrically opposed recesses arranged to pivotally receive said trunnions, and means on said head for engaging the outer sides of the free ends of said arms to restrain the same against expansion.

11. In a drill of the class described, a head, a yoke having arms embracing said head and pivoted thereto intermediate their length, means on the outer ends of said arms for retaining a tool, and means having an abutment thereon for engaging the outer side of the opposite end of one of said arms to releasably secure said yoke in a plurality of positions.

In testimony whereof I hereunto affix my signature this 26th day of September, 1929.

GEORGE RAUBERSTRAUCH.
